SLEEPING BAG

Ernst Harald Wallin, Arvika, Sweden, assignor to
Cais-Marie Wallin, Arvika, Sweden

Application November 14, 1933, Serial No. 697,977
In Sweden November 17, 1932

1 Claim. (Cl. 5—343)

The present invention relates to a sleeping bag, which is very suitable to use both for civil and military purposes and also in sanatoriums. A sleeping bag fit for its purpose must be so constructed, in order to fill the requirements made upon the same, that it protects effectively also at very low temperatures, but at the same time is very easily disinfected and takes up very little space at transport and possesses a small weight. The bag according to this invention fills all of the above requirements, and is characterized substantially thereby that around its circumference the same consists of two (or more) layers of fabric, one layer, which preferably consists of a thin or loose fabric, forming a larger bag, and the other layer of fabric, which preferably consists of a coarser or closer fabric, forming a smaller bag, located in the first mentioned bag at a distance from the bottom and sides of the same and so arranged that an interspace is obtained, which is continuous or divided in the longitudinal direction of the sleeping bag by the inner layer of fabric, the said intermediate space extending from the bottom of the outer bag to the open end of the sleeping bag, and being meant to contain heat insulating material.

Four different embodiments of the invention are shown in the accompanying drawing, in which—

Figure 1 shows a perspective view of the sleeping bag according to one embodiment.

Figure 2 shows a detail of the sleeping bag according to Figure 1.

Figure 3 shows a perspective detail of the sleeping bag according to the second embodiment.

Figure 4 shows the sleeping bag according to a third embodiment in perspective.

Figure 5 shows a detail of the sleeping bag according to Figure 4.

Figure 6 shows a detail of the embodiment according to a fourth embodiment.

Figure 7 shows a perspective view of the sleeping bag when used as a stretcher.

Figure 8 is a fragmentary perspective view partially broken away illustrating the manner in which the bottom portions of the inner and outer bags of the embodiment shown, for example, in Figure 1, may be constructed.

Figure 9 is a similar view of the embodiment shown, for example, in Figure 4.

In all of the drawing figures numerals 1 and 2 indicate the two layers of fabric of the sleeping bag, the outer of which, indicated by 1, as

stated above, preferably consists of a thinner or looser fabric than the inner layer of fabric, which is indicated by 2. The outer layer may also be waterproofed. In all of the figures 3 indicates the continuous interspace or the interspace divided by the inner layer of fabric in the longitudinal direction of the sleeping bag and formed between the layers of fabric 1 and 2 and which extends from the outer bottom of the sleeping bag to the open end of the sleeping bag.

In the embodiment shown in Figure 1 the sleeping bag comprises four superimposed rectangular pieces 4, 5, 6 and 7, which have the same extension in the longitudinal and transversal direction of the sleeping bag. By means of seams 8, 9 and 10 the said pieces are firmly united along one end and two sides. Further the pieces 5 and 6 forming the inner layer of cloth 2 of the sleeping bag are firmly united with each other by seams 11, 12 and 13, which extend parallel to the seams 8, 9 and 10 but at some distance from the same.

By the above mentioned uniting of the pieces 4, 5, 6 and 7 there is formed a larger bag by the outer layer of fabric and a smaller bag by the inner layer of fabric, the latter bag being located in the first mentioned bag at a distance from the bottom and sides of the same that an interspace 3 is formed, which is divided by the inner layer of fabric 2 in the longitudinal direction of the sleeping bag and extends from the bottom of the outer bag to the open end of the sleeping bag.

In the embodiment illustrated in Figure 3 the bag consists of two round-woven, tubular portions 14 and 15, which have about the same extension in the longitudinal and cross direction of the sleeping bag, one portion 14 inserted in the other 15. The portions 14 and 15 are steadily connected with each other by seams in a similar way as described in connection with Figures 1 and 2 and the layers of fabric 1 and 2 form corresponding bags and interspaces respectively, which are found in the sleeping bag according to the last mentioned drawing figures.

The pieces 5 and 6, Figures 1 and 2, need not necessarily be of the same length as the sleeping bag. In case the said pieces are shorter than the latter, the seam 12 serves to unite the edges of the said pieces, which are adjacent to the outer bottom of the sleeping bag. In a corresponding manner the tubular portion 14, Figure 3, may be made shorter than the portion 15, the seam 12 serving to unite the edges of the

tube, which are adjacent to the outer bottom of the sleeping bag. In the last described embodiments the inner bottom of the sleeping bag formed by the inner layer of fabric 2 will thus have no connection with the outer bottom of the sleeping bag formed by the outer layer of fabric 1.

In the embodiment shown in Figure 4 the inner layer of fabric 2 forms a smaller bag 10 formed within a larger bag, which is formed by the outer layer of fabric 1. A continuous interspace 3 has thus been obtained in this embodiment. In the outer layer of fabric there is, as may be seen from the Figures 4, 5, and 6, provided a number of holes 16, adapted to make possible a releasable connection of the layers of fabric by receiving suitable fastening members secured to the inner layer of fabric. Of course different kinds of fastening members 20 may be used for this purpose. Thus for example the recesses may be shaped as button holes and on the inner layer there may be secured cords or the like, the length of which corresponds to the width of the interspace, but tons being secured at the free ends of the said cords. However, such a connection not making it possible for the person lying in the bag to move very much, it is not to be recommended.

Figures 4 and 5 show, however, a very simple 30 and appropriate connection, which will enable the person lying in the sleeping bag to move to a great extent. In the embodiment in question the connection of the layers of fabric has been effected thereby that keeper means in the 35 form of a cord is secured to the inner layer of fabric 2 in such a manner that lengthened loops 17 are formed, and that another cord 18 located on the outside of the outer layer of fabric 1 is led in proper turns down through the respective hole 16, is introduced into a loop 17 below the hole and then led upward again through the hole. The cord 18 being able to slide in and along the loops 17 and the latter being, moreover, resilient to a certain degree, 45 the connection offers a considerable room to move.

Figure 6 shows a modified keeper means, the loop 17 replaced by a ring 19, into which the cord 18 is introduced. Also in this embodiment 50 a resilient connection is obtained. To make it easier to introduce the cord into the loops or rings united with the inner layer of fabric 1 the same are made oblong, the length being so adapted with regard to the interspace 3 that the 55 loops extend through the holes 16, whereby it will be easier to introduce the cord 18 into the loops.

Figure 7 shows the sleeping bag used as a 60 stretcher, numeral 20 indicating a separable frame, the carrying poles of which are introduced into loops obtained by the uniting of the inner layer of fabric, which loops, however, just as advantageously may be disposed on the outside of the outer bag. Along its one end the 65 inner as well as the outer bag is provided with a pull fastener 23, 24 respectively. A flap 25 formed from the outer layer of fabric of the

sleeping bag is provided with loops along each of its side edges, the said loops serving to receive the respective carrying pole. The said flap will thus form the bed-head of the stretcher. A flap 26 formed from the inner layer of fabric of the 5 sleeping bag may be secured around the head of the person lying on the stretcher. Leather bands 27 disposed on the under-side of the sleeping bag and united by the side stays, the 10 said bands also being adapted to be tightened, serve as reinforcing members. Also the leather bands 28 united with the end stays of the 15 stretcher serve as reinforcing members.

The interspace 3 formed between the layers 20 of fabric is meant, while the sleeping bag is being used, to be filled with a heat insulating material. If thus the sleeping bag is used for 25 military purposes the bag may be filled before being used for instance with straw, which is removed again in the morning, after which the bag is rolled up. The bag not being voluminous, after the filling material has been removed, it is easily transported. If the bag is used in 30 sanatoriums it is, of course, very advantageous that the filling material is easily removed, because in such a case the sleeping bag may be disinfected and washed respectively more often, than if the filling material were hard to remove.

Of course, several different embodiments in 35 addition to those shown in the drawing and described above may be thought of within the scope of the invention. Thus, in the embodiment according to Figures 3 and 4 the tube 15 may be replaced by the members indicated by 4 and 7 in the drawing, without departing from 40 the fundamental idea of the invention.

Having now described my invention, what I 45 claim as new and desire to secure by Letters Patent is:

A sectional sleeping bag comprising at least 50 two layers of fabric, one layer of fabric forming an outer bag section which is open at one end only, and the other layer of fabric forming another similar although considerably smaller bag section, which is spaced from both the 55 bottom and the sides of the outer bag section, in such a manner that an interspace is provided both below and above the inner bag section when the latter is removably arranged within the outer bag section, the interspace in its longitudinal direction extending from the bottom 60 of the outer bag section and opening at the separated edges constituting the open end of the sleeping bag per se, and the said interspace when viewed in the transverse section extending completely around the inner bag section, one 65 of the bag sections being provided adjacent its side and end edges with a series of apertures, keeper means fixed relative to the other of the bag sections in the vicinity of the apertures 70 when the bag sections are arranged one within the other, and flexible tie means extending about the bag per se and across the apertures and detachably engaging the keeper means for removably maintaining the bag sections one within 75 the other.

ERNST HARALD WALLIN.
